UNITED STATES PATENT OFFICE.

FREDERICK A. WOOP, OF RICHMOND HILL, NEW YORK.

CLOTHESPIN.

Application filed December 31, 1923. Serial No. 683,650.

To all whom it may concern:

Be it known that I, FREDERICK A. WOOP, a citizen of the United States, and resident of Richmond Hill, in the borough and 5 county of Queens, city and State of New York, have invented certain new and useful Improvements in Clothespins, of which the following is a specification.

This invention relates to clothes pins, and 10 particularly to a clothes pin made of metal.

The primary object of this invention is to provide a metallic clothes pin having paramount in mind strength and durability, efficiency in operation, and economy in the 15 cost of manufacturing. Another object is to provide means for resiliently urging the clothes pin to its closed position. Still another object is to so construct the clothes pin that any danger of tearing articles of cloth- 20 ing by any of its parts is eliminated.

The details of construction of my im- 25 proved invention will be made more apparent as the description proceeds, especially when considered in connection with the ac- companying drawings wherein;

Figure 1 is a side elevation of a clothes pin constructed in accordance with my in- 30 vention;

Fig. 2 is a view taken at right angles to 35 Fig. 1;

Fig. 3 is a sectional view taken substantially on the plane indicated by the line 3-3 in Fig. 1; and,

Fig. 4 is a detail perspective view of the 40 spring member employed.

Referring now more particularly to the drawings wherein like reference characters indicate like parts, it will be noted that the clothes pin consists of two sections, 10 and 45 11, formed preferably of rust-proof metal, each section being formed with flat surfaces 12, which abut when the pin is closed, and semi-cylindrical outer surfaces 13, thus simulating substantially the shape of the 50 clothes pins now universally used. Each of the clothes pin sections, 10 and 11, are tapered at their lower end and flared out- wardly, as at 14, to facilitate the position- ing of the clothes pin over the clothes and 55 clothes line.

The clothes pin section 10 is provided with a pair of spaced ears 15, while the clothes pin section 11 is formed with a cor- 60 responding pair of ears 16, the ears on the 55 two clothes pin sections being so arranged that they lie adjacent one another in co-

operative relation, as clearly illustrated in Fig. 3. These ears are provided with aligned perforations, through which passes a pin 17, preferably headed at both ends, as 60 at 18, whereby the clothes pin sections are pivotally connected together.

For resiliently maintaining the clothes pin sections in closed position there is pro- 65 vided a separate spring member 19, formed with a pair of laterally extending spaced ears 20, which ears are apertured as at 21 for the accommodation of the pivot pin 17. The spring member 19 is preferably made of resilient metal and bowed as at 22 and 70 23 in opposite directions. The upper end of the clothes pin section 10 is shaped as at 24 to engage the bowed portion 22 of the spring member, while the upper extending end 25 of the clothes pin section 11 is en- 75 gaged by the bowed or curved portion 23 of the spring member.

The clothes pin section 10 extends up- 80 wardly and terminates in a curved or hook- shaped end or cap 26, which overlies the upper end 25 of the other clothes pin section as well as the spring in the manner clearly illustrated in Figs. 1 and 2.

As shown, this end cap 26 has a groove 85 27 which besides enclosing the upper ends 23 and 25 of the spring and member 11 to prevent the ends of these parts from tearing the articles of clothing, is of such length as to permit movement of the movable parts within proper limits. 90

Obviously, by compressing the upper ends 95 of the clothes pin sections, 10 and 11, the lower ends are caused to open, whereupon the pin may be forced downwardly over the article of clothes and the clothes line to hold the same in the well known manner. The tension of the spring 19, which is nor- 100 mally exerted to maintain the clothes pin sections in closed position, as illustrated in Fig. 1, is sufficient to maintain the clothes pin in engagement with the clothes and line and securely hold the clothes on the line. 105

The manufacture of the clothes pin may be effected inexpensively and with facility, owing to the fact that the clothes pin com- 110 prises only four separate parts. It should furthermore be noted that the clothes pin is made of metal, which will not rust, freeze, or become easily damaged, thereby insuring its durability in use.

While one embodiment of the invention has been described in detail, reservation is

made to make such minor changes in the details of construction as may come within the purview of the accompanying claims.

Having thus described my invention 5 what I claim is:

1. In a clothes pin of the class described, a pair of clothes pin sections, ears formed with registering apertures extending from said sections, a spring formed with a pair 10 of apertured ears, a pivot pin extending through the aligned apertures in the ears of said clothes pin sections and spring, said spring being shaped to bear respectively against the opposed faces of said clothes pin 15 sections.

2. An article of manufacture comprising a metallic clothes pin formed in two sections, each section being formed with a pair of laterally extending apertured ears, the 20 ears of the two clothes pin sections being arranged in co-operative relation with their apertures in alignment, a spring member formed with a pair of apertured ears extending laterally therefrom, a pivot pin extending 25 through the aligned apertures of the ears of said clothes pin sections and spring, said spring member for pivotally connecting the clothes pin sections, said spring member being bowed and adapted to engage adjacent 30 faces of the clothes pin sections at one end thereof.

3. A clothes pin formed of non-rustable metal and comprising two sections formed with opposed flat surfaces and flared ends, 35 each clothes pin section being formed with a pair of laterally extending apertured ears arranged in co-operative relation with one another, a spring member formed with a pair of ears adapted to extend between the 40 pairs of ears of said clothes pin sections, the upper ends of said clothes pin sections being spaced, said spring member engaging the opposed spaced ends of said clothes pin sections, one of said clothes pin sections being formed 45 with a hook-shaped end extending over the adjacent end of the other clothes pin section.

4. A clothes pin formed of non-rustable metal and comprising two sections formed with opposed flat surfaces and flared ends, 50 each clothes pin section being formed with a pair of laterally extending apertured ears arranged in co-operative relation with one

another, a separate substantially flat spring member formed with a pair of ears adapted to extend between the pairs of ears of said clothes pin sections, the upper ends of said clothes pin sections being spaced from each other, said spring member engaging the opposed spaced ends of said clothes pin sections, one of said clothes pin sections being 60 longer than the other and formed with a hook-shaped cap extending over the adjacent end of the other clothes pin section and enclosing the end of said spring, said cap having a groove of sufficient length to permit the clothes pin sections to move to open and closed positions and at all times protecting the ends of said spring and shorter clothes pin section against interference with articles of clothing. 65

5. In a clothes pin of the class described, a pair of clothes pin sections, ears formed with registering apertures extending from said sections, a spring formed with a pair of apertured ears, a pivot pin extending 70 through the aligned apertures in the ears of said clothes pin sections and spring, said spring being shaped to bear respectively against the opposed inner faces of said clothes pin sections, and means for enclosing the upper ends of said spring and one of said clothes pin sections to prevent interference with articles of clothing. 75

6. An article of manufacture comprising a metallic clothes pin formed in two sections, each section being formed with a pair of laterally extending apertured ears, the ears of the two clothes pin sections being arranged in co-operative relation with their apertures in alignment, a spring member formed with a pair of apertured ears extending laterally therefrom, a pivot pin extending through the aligned apertures of the ears of said clothes pin sections and spring member for pivotally connecting the clothes pin sections, said spring member being bowed and adapted to engage adjacent faces of the clothes pin sections at one end thereof, and the upper end of one of said clothes pin sections overlying the upper ends of the opposite section and spring to prevent interference with articles of clothing. 95 100

In testimony whereof I affix my signature.
FREDERICK A. WOOP.
